Attorney

UNITED STATES PATENT OFFICE.

PETER IACULLI, OF BOSTON, MASSACHUSETTS.

MEANS FOR ATTACHING HEELS.

1,279,871.

Specification of Letters Patent. Patented Sept. 24, 1918.

Application filed May 22, 1918. Serial No. 236,239.

To all whom it may concern:

Be it known that I, PETER IACULLI, a subject of the King of Italy, and a resident of the city of Boston, in the county of Suffolk and Commonwealth of Massachusetts, have invented certain new and useful Improvements in Means for Attaching Heels, of which the following is a full, clear, and exact specification.

- 10 The object of my invention is the effecting of improved means for attaching heels of the so-called French and Cuban types, and heels of other forms as well, to the shoes worn by ladies and misses.
- 15 Heels as attached to shoes previous to my invention are quite insecure, being very liable to getting pulled off by catching in some crack in the paving. Further, there is constant danger from the tacks ordinarily 20 driven down through the sole into the heel for fastening the latter in place. The heads of these tacks or nails quickly become rusted from the moisture of the feet, and stain and rot the hose, and become liable to infect the 25 wearer with lock-jaw or blood poisoning through a scratch which they may give in the feet.

In addition to the tacks or nails usually employed, the heels are glued to the shoe- 30 soles, the same being done before the tacks are driven in. Consequently, clamps have to be used for tightly confining the heels to the soles until the glue has become thoroughly hardened, frequently entailing a de- 35 lay of a day before the clamps can be removed and applied to other shoes.

Moreover, in thus applying heels to satin shoes, or silk shoes or those all white or with white heels, the glue is very liable to 40 spread over onto the delicate surfaces and ruin the shoes.

In my improved construction, I provide an attaching means which saves the delay caused by waiting for glue to dry, which 45 permits of the omission of glue for shoes or heels having delicate surfaces, which has no tack-heads liable to injure the hose or feet, and which will hold the heels firmly against accidental disconnection.

50 Referring to the drawings forming part of this specification, Figure 1 is a side sectional view of a shoe of the pump style having its heel attached thereto by my improved means. Fig. 2 is a face view of a gage used 55 in accurately locating the heel, a portion of the under surface of the shoe and of the

attaching device being also shown. Fig. 3 is a perspective view of the gage. Fig. 4 is a perspective view of the nail comprising a large part of the attaching means, Fig. 5 is a face view of the metal plate used in conjunction with the nail. Fig. 6 is a side sectional view of a leather heel and its attaching means. Fig. 7 is a side sectional view showing the means for attaching a so-called Cuban heel to a shoe. Figs. 8 and 9 are perspective views of said means.

Considering first the French heel shown in Fig. 1, the reference numeral 1 designates the shoe upper, 2 the inner sole, and 3 the heel. To the under surface of the inner sole is attached a metal plate 4 by means of tacks or nails 8 driven through the holes 5, 6 into the inner sole. At the approximate center of the plate 4 is a square hole 7 for the passage of a nail 9, which is made similar in cross section but which tapers to a point, as illustrated in Fig. 4. The head 10 of this nail is preferably circular and comparatively large in diameter, but thin and flat.

By having the nail 9 thus made square in cross section, it holds with much greater tenacity when driven into the wood of which the heels are now most generally composed and it also cuts its way more easily into the small hole which has been drilled for it in the heel.

For accurately locating the heel on the sole, I employ a gage 12, shown in Figs. 2 and 3, consisting of a thin body of metal or other suitable material, whose edge corresponds in outline to the heel portion of the insole 2, and through whose approximate center is a hole 13 approximately fitting the base of the nail 9, but slightly longer than it is wide. Between this hole and the edge 14 is a transverse slot 15.

This gage is used as follows: It is necessary to bore a hole in the heel 3 at a point to receive the nail 9, and for this purpose 100 the gage is laid upon the heel with the edges of both coinciding, so that the hole can be accurately located by drilling through the hole 13.

The gage is then used for accurately locating the nail 9 on the shoe, this being done by first putting the nail through the hole 7 of the metal plate 4 and then through the hole 13 of the gage. All three parts are next laid on the shoe sole, with the point 110 of the nail projecting outward, and the curved edge of the gage coinciding with

the outline of the heel portion of the sole. The slot 15 being located to leave the small holes 6 of the plate 4 exposed, small nails or tacks are driven through these holes into

5 the shoe sole, after which the gage can be removed without disturbing the metal plate.

After driving small nails through the holes 5 into the sole, by which the plate, and hence the nail, are firmly secured to 10 the shoe, the point of the nail is introduced in the hole drilled in the heel, and driven forcibly in until sole and heel are snugly together. In doing this it is well to moisten the nail before driving it in, both to render 15 it easier in driving, and to make it hold more securely by means of the rust which will form thereon. Finally a couple of nails 16 are driven through the overhang 17 into the sole, and the task of attaching the heel 20 is practically complete. If still greater security is desired, glue can be applied to the surfaces before fastening them together.

For leather heels 20, a metal plate is dispensed with, and three nails 9 like that 25 above described, are inserted through the rear part of the outer sole 21 before it is applied to the insole 2, a gage similar to that above described being employed for correctly locating the nails both in the heel 30 and outer sole. The two soles are secured together by tacks or nails in the usual manner. I also use one of the nails 9 for strongly fastening the heel-lifts together, the same being driven in before the outer 35 one or two lifts are tacked on, as shown in Fig. 6.

For the attachment of the Cuban heel 25 illustrated in Fig. 7, a metal plate 4 and nail 9 are used in substantially the same 40 way as first described, but since this type of heel has no overhang 17, I drive two wire nails 26 down into the heel, snipping off their heads to leave sharp ends projecting a short distance above the heel. Then, when

the sole is forced down upon the heel, these 45 nail ends are driven into the shoe sole, and so take the place of the nails 16.

What I claim is:

1. The combination with a shoe or the like having an inner sole, of a flatly extended member attached to said inner sole, a tapered nail projecting from said member and having a thin extended head between said member and inner sole, and a heel penetrated by said nail and mainly 55 held in place by the same.

2. The combination with a shoe or the like having an inner sole, of a flatly extended member attached to said inner sole, a tapered nail projecting from said member and having a thin extended head between said member and inner sole, and a heel penetrated by said nail, said nail being 60 square in cross section.

3. The combination with a shoe or the like, of a metal plate having small nail holes near its edge and a central larger hole, the plate being fastened to the shoe-sole by suitable devices passing through said small holes, a tapered nail passing through 70 said central hole and having a thin flat head between the plate and shoe-sole, and a heel penetrated by said nail.

4. The combination with a shoe or the like, having a sole, of a metal plate having 75 small holes near its edge and a central square hole, nails passing through said small holes into the shoe-sole, a nail sharply pyramidal and square in cross section to fit said square hole at its base, the nail having 80 a thin flat extended head between said plate and sole, and a heel penetrated by said nail and mainly fastened thereby to the shoe.

In testimony that I claim the foregoing invention, I have hereunto set my hand this 85 7th day of May, 1918.

PETER IACULLI.
